UNITED STATES PATENT OFFICE.

WILLARD L. POLLARD, OF EVANSTON, ILLINOIS.

DESIGN FOR AN AUTOMOBILE.

60,568.

Specification for Design.

Patented Mar. 7, 1922.

Application filed January 16, 1920. Serial No. 351,953. Term of patent 3½ years.

To all whom it may concern:

Be it known that I, WILLARD L. POLLARD, a citizen of the United States, residing at Evanston, in the county of Cook and State of Illinois, have invented a new and original and ornamental Design for Automobiles, of which the following is a specification, reference being had to the accompanying drawing, forming a part thereof.

I claim:

The ornamental design for an automobile as shown.

WILLARD L. POLLARD.
